Primary Examiner — Susan Bennett Hattan*Assistant Examiner* — Brett Miller(74) *Attorney, Agent, or Firm* — Buche & Associates, P.C.; John K. Buche; Bryce A. Johnson(57) **CLAIM**

A bud trimmer, as shown and described.

DESCRIPTION

FIG. 1 is a perspective view of a bud trimmer.

FIG. 2 is a front view of the trimmer of FIG. 1.

FIG. 3 is a rear view of the trimmer of FIG. 1.

FIG. 4 is a left side view of the trimmer of FIG. 1.

FIG. 5 is a right side view of the trimmer of FIG. 1.

FIG. 6 is a top view of the trimmer of FIG. 1.

FIG. 7 is a bottom view of the trimmer of FIG. 1; and,

FIG. 8 is an exploded view of the trimmer of FIG. 1.

The broken lines depict portions of the bud trimmer that form no part of the claimed design.
